UNITED STATES PATENT OFFICE.

OTTO HOFFMANN, OF NEW ALBANY, INDIANA.

FOLDING BASKET OR FRUIT-BOX.

SPECIFICATION forming part of Letters Patent No. 716,231, dated December 16, 1902.

Application filed September 15, 1902. Serial No. 123,538. (No model.)

To all whom it may concern:

Be it known that I, OTTO HOFFMANN, a citizen of the United States, residing at New Albany, in the county of Floyd and State of Indiana, have invented a new and useful Folding Basket or Fruit-Box, of which the following is a specification.

This invention relates to folding baskets or fruit-boxes.

10 The object of the invention is to provide a basket or box which shall combine simplicity of construction, efficiency and durability in use, and readiness of manufacture and which without separation of any of its parts may be 15 set up or collapsed, as required.

With these and other objects in view, as will appear as the nature of the invention is better understood, the same consists in the novel construction and combination of parts 20 of a folding basket or fruit-box, as will be hereinafter fully described and claimed.

In the accompanying drawings, forming a part of this specification, and in which like numerals of reference indicate corresponding 25 parts, there is illustrated one form of embodiment of the invention capable of carrying the same into practical operation, it being understood that the elements therein exhibited may be varied or changed as to shape, proportion, 30 and exact manner of assemblage without departing from the spirit thereof.

In the drawings, Figure 1 is a view in perspective of the frame or body of the basket or box and showing the position of the parts 35 when set up for use. Fig. 2 is a similar view showing the parts collapsed. Fig. 3 is a view in transverse section showing the manner of associating the cover with the basket or box frame.

40 The frame of the basket or box is constructed either of thin strips of wood or metal or a combination of both, metal being indicated in this instance, and comprises longitudinal top and bottom frame-pieces 1 and 2, respectively, vertical end pieces 3 and 4, respectively, corner-cleats 5 5^a, a bottom-brace 6, and a bail 7. All of these parts are connected by rivets 8, the corner-cleats being adapted to be swung on their pivots to cause them to 45 cover the upper and lower edges of the side pieces, one of which adjustments is indicated by dotted lines in Fig. 1, or to cover the up-

per and lower outer edges of the end pieces 3. These corner-cleats not only subserve the function of braces for preventing the frame 55 from spreading in use, but also operate to reinforce the covering 9 at the corners, the latter function being of particular importance where the covering is of paper, as will be apparent. From a standpoint of cheapness it 60 will generally be preferred to employ a stiff paper covering; but cloth, canvas, or any other suitable fabric or material may be employed and still be within the scope of the invention.

65 The bail 7 has its terminals pivoted to the inner sides of the frame-pieces 1, thus to permit it to be folded in between such pieces when the structure is collapsed, as shown in Fig. 2; but the bail may be otherwise associated with the frame-pieces or may instead of being constructed of flat metal, as shown, be a length of wire connected with the frame-pieces in the usual manner.

70 The structure of this invention is exceedingly light, but at once strong and durable, and will be found peculiarly adapted for the shipment of fruits that are easily bruised in transit, for the reason that only a very small percentage of the fruit will be impinged by 75 hard surfaces—an advantage over slatted crates of the ordinary construction.

In associating the cover with the frame if the same be of paper the sides and ends of the covering will be folded around the frame 80 members and pasted together, and where a textile fabric is employed as a covering it may be sewed upon the frame, as shown in Fig. 3.

85 While the device of this invention is an exceedingly simple construction, it will be found of the highest efficiency and durability in use and may be manufactured and sold at a price that will place it within reach of persons having use for such structures.

90 Having thus fully described my invention, what I claim as new, and desire to secure by Letters Patent, is—

95 1. A basket or fruit-box comprising longitudinal top and bottom frame-pieces, vertical 100 end pieces, a pivoted bail associated with the top frame-pieces, and adjustable corner-cleats associated with the frame-pieces and end pieces, said parts being connected for pivotal

movement with relation to each other, and a transverse brace connecting the intermediate portions of the bottom frame-pieces.

2. A basket or fruit-box comprising a collapsible frame having adjustable corner-cleats, in combination with a covering secured to the members of the frame and protected at its corners by the cleats.

In testimony that I claim the foregoing as my own I have hereto affixed my signature in the presence of two witnesses.

OTTO HOFFMANN.
